UNITED STATES PATENT OFFICE.

JOSIAH R. KIDNEY, OF EAST HAMPTON, CONNECTICUT, ASSIGNOR TO THE N. N. HILL
BRASS CO., OF EAST HAMPTON, CONNECTICUT, A CORPORATION.

TELEPHONE TOY.

Application filed May 15, 1922. Serial No. 560,880.

To all whom it may concern:

Be it known that I, JOSIAH R. KIDNEY, a citizen of the United States, residing at East Hampton, in the county of Middlesex 5 and State of Connecticut, have invented a new and useful Improvement in Telephone Toys; and I do hereby declare the following, when taken in connection with the accompanying drawings and the characters 10 of reference marked thereon, to be a full, clear, and exact description of the same, and which said drawings constitute part of this application, and represent, in—

Fig. 1 a side view of a telephone toy constructed in accordance with my invention.

Fig. 2 a face view of the upper end of the same.

Fig. 3 a vertical, sectional view through the transmitter.

Fig. 4 a sectional view on the line 4—4 of Fig. 1.

Fig. 5 a perspective view of the transmitter-arm detached.

Fig. 6 a side view of the connecting screw detached.

Fig. 7 a face view of one of the transmitter-disks detached.

Fig. 8 a face view of another transmitter-disk detached.

Fig. 9 a rear view of the transmitter shell detached.

This invention relates to improvement in telephone toys, and particularly to toys simulating in appearance a desk telephone instrument, such, for instance, as shown in my Patent No. 1,419,632, June 13, 1922.

Toys of the telephone type are provided with a transmitter mouth-piece, and it is desirable that this mouth-piece should be removable, not only to permit it to be sterilized, but for convenience in assembling. The object of this invention is to provide a toy telephone with a removable mouth-piece, and the invention consists in the construction as hereinafter described and particularly recited in the claims.

As in the application above referred to, the toy consists of a post 10 mounting a bell 11. Mounted in the top of the post is a pair 50 of fingers 12 and 13, between which is mounted an arm 14, which is connected between the fingers by a rivet 15. This arm 14 is formed with shoulders 16 and 17, and with a longitudinal slot 18 extending inward 55 from its outer end to a semi-circular

recess 19. Located in the slot 18 is a screw 20, the head 21 of which enters the recess 19 and is formed in its under face with lugs 22, which prevent the screw from turning in the arm. The end of the screw extends beyond the outer end of the arm and together are passed through the shell 23 of a transmitter and through disks 24 and 25 applied to the open face thereof, these disks being provided with centrally-arranged clearance- 60 openings 26 and 27, and the end of the screw enters a threaded hole 28 formed for it in the center of a mouth-piece 29, which, when turned on to the screw, comes to a bearing against the disks 25 and 26 and 65 clamps the shell 23 in place. In turning the mouth-piece onto the screw, the lugs 22 come to a bearing against opposite faces of the arm 14, and thus is held against rotation. 70

With this construction, the mouth-piece 75 may be readily removed when desired, and the parts are assembled and connected together in a firm manner without riveting.

I claim:

1. A telephone toy comprising a post, an 80 arm pivotally mounted in the top thereof, said arm formed with a recess and with a groove entering the outer end of the arm and intersecting said recess, a screw having its head entered into said recess and extending forward into said groove and beyond the said arm, a shell mounted on said arm, a disk closing the outer end of said shell, and a mouth-piece turned onto the end of said screw. 85

2. A telephone toy comprising a post, an arm pivotally mounted in the top thereof, said arm formed with a recess and with a groove entering the outer end of the arm and intersecting said recess, a screw having 90 its head entered into said recess and provided in its under face with lugs, and extending forward into said groove and beyond the said arm, a shell mounted on said arm, a disk closing the outer end of said shell, and a mouth-piece turned onto the end of said screw. 95

In testimony whereof, I have signed this specification in the presence of two subscribing witnesses.

JOSIAH R. KIDNEY.
